No. 712,769.

Patented Nov. 4, 1902.

S. A. CRONE.

END SILL FOR CARS.

(Application filed July 5, 1902.)

(No Model.)

UNITED STATES PATENT OFFICE.

SETH A. CRONE, OF NEW YORK, N. Y.

END SILL FOR CARS.

SPECIFICATION forming part of Letters Patent No. 712,769, dated November 4, 1902.

Application filed July 5, 1902. Serial No. 114,399. (No model.)

To all whom it may concern:

Be it known that I, SETH A. CRONE, a citizen of the United States, and a resident of New York, in the county of New York and State of New York, have invented certain new and useful Improvements in End Sills for Cars, of which the following is a specification.

The invention relates to improvements in railway-cars, and pertains more particularly to a novel construction for the end sills of such cars, the purpose of the invention being to provide a trussed end sill of special construction which may be used conveniently and advantageously and without interference with the necessary parts carried at the ends of cars.

My invention comprises, among other features, an end sill having a beam or plate extending from side to side of the car at the end of the latter and comprising in one integral piece a truss member extending downwardly on converging lines toward the center of the car and to a suitable extent to permit of an adequate space being formed between the sill proper and the upper edge of the truss member to receive the body of the usual coupler. The beam or plate for the end sill will be an ordinary rolled beam or merchant-plate slit in line with its length except at its end portions and the metal at one side of the said slit being bent downward to form the integral truss member.

The invention will be fully understood from the detailed description hereinafter presented, reference being had to the accompanying drawings, in which—

Figure 1 is an elevation of an end sill, partly broken away, constructed in accordance with and embodying the invention. Fig. 2 is a top view of same, a portion of the draw-sills being illustrated in position. Fig. 3 is an enlarged vertical section of same on the dotted line 3-3 of Fig. 1. Fig. 4 is an elevation of a modified form of the invention, and Fig. 5 is a vertical section of same on the dotted line 5-5 of Fig. 4.

Referring to Figs. 1, 2, and 3, 10 designates the end sill for a car, said sill being in one integral piece and formed from a rolled channel-beam of commercial shape slit along the

line 11 to form the horizontal member 12 and truss member 13, the latter being bent downwardly on converging lines, as shown in Fig. 1, to constitute a truss of substantial character, the truss member 13 being integral with the member 12 by reason of the fact that the slit along the line 11 does not extend through the end portions of the beam. The end sill shown in Figs. 1, 2, and 3 is thus in one integral piece and made from a rolled channel-beam, whose upper and lower flanges 14 15 receive between them at the opposite sides of the longitudinal center of the car the ends of the draw-sills 16 16. Between the central portion of the upper and lower flanges 14 15 of the end sill and between the parallel draw-sills 16 are provided the filling-pieces 17 18 19, the piece 17 being in the form of a hollow casting fitting below the upper flange 14 and extending downwardly to the lower edge of the upper member 12 of the end sill and the filling-piece 19 being in the form of a hollow casting fitting above the flange 15 and extending upwardly to the upper edge of the truss member 13 of the end sill, while the filling-piece 18 is also in the form of a hollow casting of general rectangular outline fitting between the upper and lower members 12 13 and upper and lower filling-pieces 17 19, said filling-piece 18 having an opening 20 for the passage of the body of the usual coupler. The filling-pieces 17 and 19 are secured by being riveted to the end sill and draw-sills, and the filling-piece 18 is detachably secured, by means of the bolts 21, to the draw-sills 16. The purpose of detachably securing the filling-piece 18 is to enable it to be reversed in position or turned upside down between the sill members 12 13, so that when desired the opening 20 in said filling-piece 18 may be brought directly below the upper member 12 instead of, as shown in Fig. 1, directly above the lower member 13, this reversibility of the filling-piece 18 being desirable, so as to adapt the opening 20 therein to the position of the coupler. For a car built low it would be necessary that the filling-piece 18 be reversed in position, so that the opening 20 may come at the upper edge thereof, where it would be adapted to receive the body of the coupler; but for very many cars the filling-piece 18

would be given the position shown in Fig. 1, with the opening 20 directly above the truss member 13. The filling-pieces 17, 18, and 19 very materially strengthen the central portion of the end sill and form durable structures capable of withstanding the action of the coupler members.

Upon the ends of the end sill are secured buffers 22.

10 The end sill shown in Fig. 4 is adapted for wooden cars, and the novelty in the structure disclosed in Fig. 4 consists in slitting the usual wooden end sill and interposing between the sections 25 25 thereof the metal plate in one integral piece comprising the upper horizontal member 26 and truss member 27, the latter being formed by slitting the plate as with respect to the structure of Fig. 1 and bending downward one section of the 15 plate along the line of said slit to form the truss member 97, the latter affording great strength and durability and there being provided above its upper edge a suitable space for the coupler members. The wooden portions 20 of the sill shown in Figs. 4 and 5 may be recessed, as at 27, to afford additional space for the coupler members, said recess 27 terminating at the lower edge of the upper member 26 and said member 26, together 25 with the truss member 27, affording sufficient strength to the end sill to prevent the formation of the recess 27 from prejudicially weakening the end sill at its central portions.

In each of the constructions shown in the drawings an end sill is presented having as its essential feature a trussed metallic section in one integral piece formed by slitting the beam or plate longitudinally except at its ends and bending downwardly one division 30 of the beam or plate along the line of the slit to form the truss member, the said metallic section being formed from either a commercial rolled beam or a merchant-plate of known construction. The said metallic section materially adds to the strength and longevity of the end sill and adjacent car structure without materially increasing the cost of the latter.

In the process of manufacturing the end sill it may be desirable while bending downwardly the truss member to avoid stretching the metal in said truss member, and this may be readily accomplished by upsetting the upper metallic member of the end sill during and in the proportion to the bending downward of the truss member, this upsetting of the upper member of the end sill being performed by the pressing toward each other in a well-known way of the ends of the beam or plate during the downward bending of the 60 truss member.

The metallic section of the end sill is arranged on edge, as shown, whether of the flanged rolled beam or merchant-plate construction, and when the end sill is formed 65 from a flanged rolled beam for use in metal cars the lower central portion of the truss member 13 will be horizontal and parallel

with the upper member 12, as shown in Fig. 1, so as to afford adequate space for the ends of the draw-sills, the filling-pieces, and the 70 coupler parts.

What I claim as my invention, and desire to secure by Letters Patent, is—

1. The end sill for cars comprising in one integral piece the metallic section having the 75 upper horizontal member and the lower truss member, the latter being formed by slitting the beam or plate, except at its end portions, and bending that section of said beam or plate at one side of said slit in a direction 80 therefrom; substantially as set forth.

2. The end sill for cars comprising the flanged rolled beam slit lengthwise through its web, except at its end portions, the section of said beam at one side of said slit being bent to form the truss member 13, while the section at the other side of said slit constitutes the horizontal member 12; substantially as set forth.

3. The end sill for cars comprising in one 90 integral piece the flanged rolled beam slit longitudinally, except at its ends, and having one section thereof bent in a direction from said slit to form the truss member, while the other section thereof constitutes the horizontal member, combined with the draw-sills at the opposite sides of the center of said end sill, and a metallic filling secured intermediate the upper and lower flanges of the end sill and the vertical facing sides of the draw-sills, said filling having an opening 95 therein for the coupler; substantially as set forth.

4. The end sill for cars comprising the flanged rolled beam slit lengthwise through its web, except at its end portions, the section of said beam at one side of said slit being bent to form the truss member 13, while the section at the other side of said slit constitutes the horizontal member 12, combined with the draw-sills at opposite sides of the 105 center of said end sill, and a metallic filling secured intermediate the upper and lower flanges of the end sill and the vertical facing sides of the draw-sills, said filling comprising the upper piece 17, the lower piece 19, and the 110 intermediate piece 18, having the opening 20 and secured to said draw-sills; substantially as set forth.

5. The end sill for cars comprising the flanged rolled beam slit lengthwise through 120 its web, except at its end portions, the section of said beam at one side of said slit being bent to form the truss member 13, while the section at the other side of said slit constitutes the horizontal member 12, combined 125 with the draw-sills at opposite sides of the center of said end sill, and a metallic filling secured intermediate the upper and lower flanges of the end sill and the vertical sides of the draw-sills, said filling comprising the 130 upper piece 17, the lower piece 19, and the intermediate piece 18, having the opening and detachably secured to said draw-sills and being reversible so that said opening may be

brought directly over the said truss member or directly below the said horizontal member of the end sill; substantially as set forth.

6. The end sill for cars comprising the flanged rolled beam slit lengthwise through its web, except at its end portions, the section of said beam at one side of said slit being bent therefrom to form the truss member 13, while the section at the other side of said slit constitutes the horizontal member 12, the said truss member 13 being on lines converging downwardly toward the center of the end sill

where a portion of said truss member is on a horizontal plane and parallel with the upper member 12, whereby adequate provision is made for the parallel draw-sills of the car; substantially as set forth.

Signed at New York, in the county of New York and State of New York, this 3d day of July, A. D. 1902.

SETH A. CRONE.
